CLAIM

The ornamental design for a tripod salad cutter, as shown and described.

DESCRIPTION

FIG. 1 is a perspective view of tripod salad cutter showing my new design.

FIG. 2 is a front view thereof.

FIG. 3 is a rear view thereof.

FIG. 4 is a right end view thereof.

FIG. 5 is a left end view thereof.

FIG. 6 is a top view thereof.

FIG. 7 is a bottom view thereof; and,

FIG. 8 is a perspective view in an open position thereof.

The broken lines are for illustrative purposes only and form no part of the claimed design.
